PRIME MOVER AND CONTROLLING MEANS
THEREFOR

Alexander D. Ferguson, Michigan City, Ind., assignor to Sullivan Machinery Company, a corporation of Massachusetts

Application April 14, 1936, Serial No. 74,289

23 Claims. (Cl. 121—127)

My invention relates to steam driven pumping apparatus and more particularly to the steam driving devices for such apparatus, whereby a controlled delivery of pumped fluid may be effected.

It is an object of my invention to provide an improved, steam-driven pumping apparatus. It is another object of my invention to provide an improved steam engine valve gear. It is a further object of my invention to provide an improved governing device for a compressor or other pump driving engine. It is a still further object to provide an improved combined speed and delivery-pressure control for a pump-driving engine. It is yet another object of my invention to provide an improved exhaust valve gear for an engine which may have occasion to operate either condensing or non-condensing. Other objects and advantages of the invention will hereinafter appear from the specification and the claims.

In the accompanying drawings, in which one embodiment of my invention is shown for purposes of illustration:

Fig. 1 is a fragmentary side-elevational view of a steam-driven compressor in which my invention is embodied in its illustrative form;

Fig. 2 is a vertical longitudinal section through a portion of the valve-actuating and controlling mechanism;

Fig. 3 is a horizontal section through a portion of the valve actuating mechanism, some parts being shown in elevation and some broken away, and the section being taken on the plane of the section line 3—3 of Fig. 1;

Fig. 4 is an enlarged fragmentary section on the plane of the line 4—4 of Fig. 1 showing the exhaust valve control devices;

Fig. 5 is a fragmentary section on the plane of line 5—5 of Fig. 4;

Fig. 6 is a fragmentary section on the plane of the line 6—6 of Fig. 4;

Fig. 7 is a perspective view of a cam for controlling "compression" during condensing operation;

Fig. 8 is a perspective view of a cam for controlling "compression" during non-condensing operation;

Fig. 9 is a perspective view of a cam for controlling admission and cut-off;

Fig. 10 is a fragmentary vertical section on the plane of the line 10—10 of Fig. 4;

Fig. 11 is a central vertical section through the steam cylinder of the apparatus shown in Fig. 1;

Fig. 12 is a vertical transverse section on the

plane of the line 12—12 of Fig. 11 showing details of an admission valve;

Fig. 13 is a vertical transverse section through the steam cylinder, showing an exhaust valve, the section being taken on the plane of line 13—13 of Fig. 1;

Fig. 14 is a fragmentary vertical sectional view through an exhaust valve actuating mechanism;

Fig. 15 is a view similar to Fig. 14 but showing relative positions of the valve actuating mechanism with the exhaust valve open;

Fig. 16 is a detail section on an enlarged scale showing the admission valve packing.

Referring to the drawings, it will be noted that Fig. 1 shows portions of a so-called angle-compound compressor in which the illustrative embodiment of my invention is incorporated. This compressor comprises a horizontal low-pressure cylinder 1 and a vertical high-pressure cylinder, not shown, but supported upon a pedestal 2 which is mounted upon a crank case 3. A steam driving cylinder 4 is mounted between the low pressure cylinder 1 and the crank case 3. As shown in Fig. 11, the steam cylinder 4 is provided with a bore 5 in which a piston 6 is reciprocable. Piston 6 has a horizontal piston rod 7, whose left hand end is operatively connected to and drives the fly wheel 8 and whose right hand end extends, as indicated at 9, into the low pressure compressor cylinder 1 and moves the piston (not shown) in the latter. The steam cylinder has heads 11 and 12, each of which has a live steam space 13 therein, and each of which has associated with it an admission valve mechanism 14. The cylinder is suitably jacketed as at 15. Referring to the crank end of the cylinder, a section through which is shown in Fig. 12, it may be noted that live steam is conducted from a supply line 17, under control of a stop valve 18, through one of the branched supply connections 19 into the live steam space 13. The cylinder head is provided with suitable portions 20 which form a cylindrical housing 21 grooved as at 22 between its ends, the groove 22 communicating through a suitable passage 23 with the bore of the cylinder. Within a bore in the housing 21 there is mounted a cage 25, providing coaxial, longitudinally-spaced seats 26 and 27 for a double-beat poppet valve 28 controlling the admission and cut-off of steam to the crank end of the cylinder. The valve 28 is of built up construction, and has a generally annular body 29 having an integral seating portion 30 to cooperate with the seat 26, and an upper, flexibly-mounted seat portion 31, in the form of a

50
55

thin annulus or flange held in position by a collar 32.

Fig. 13 illustrates the provision for the control of exhaust. The cylinder 4 is provided, at 5 zones each spaced materially from the ends thereof and also from the central zone thereof, with exhaust ports of which one is shown in Fig. 13 at 35. These exhaust ports, which may be suitably gridded, communicate with seats 37, upon 10 which exhaust-port-controlling valves 38 are adapted to seat. Passages 39 through the valve seat 37 open into an exhaust steam chamber 40 comprising branches respectively serving to conduct the exhaust steam from the different exhaust 15 ports to a central exhaust space 41, which may be connected through a suitable connection 42 to a condenser, to an exhaust steam outlet, or other suitable points as desired.

The admission valves 28 and the exhaust valves 20 38 are respectively mounted upon valve stems 43 and 44. The valve stem 43 is provided with a longitudinally extending packing 45 in a sleeve portion 46 formed integral with the valve cage 25. The exhaust valve stem 44 passes through a suitable sealing plug 46.

The valve stems 43 and 44 are each cam-actuated, and it is unnecessary to go into detailed description of both an inlet and an exhaust valve stem housing structure, as these are generally 30 similar. It will be noted that housings 48 are provided to inclose the valve stems as shown in Fig. 14; and these housings provide suitable cylindrical guide and spring housing portions 50 aligned with the valve stems. In the guide portion proper 51 of these portions 50 is a guide member 52 directly connected as at 53 to one of the valve stems. A spring 54 housed in the spring housing portion 50 acts between a shoulder 55 on the latter and a shoulder 56 on the guide member 40 52, and normally maintains the valve elements closed by moving the valve stems to valve closing position. The guide members 52 carry cam engaging rollers 57, which are engaged by different cam devices in the case of the different valves. 45 Suitable lubrication means is indicated at 58 to permit the supply of lubricant to the guides and rollers.

An appropriate housing 60 supporting a series of ball thrust bearings 61 is mounted upon the 50 valve stem housing members 48, and incloses a valve actuating cam shaft 62. The cam shaft, which is hollow, is connected by a suitable coupling device 63 to an aligned driving shaft 64, carrying one of a pair of helical gears 65 and 66, 55 the other of which is supported and rotated by the compressor crank shaft. It will be observed that these gears are of the same size and as a result the cam shaft 62 makes a revolution for each revolution of the crank shaft. The cam shaft 62 supports a pair of admission valve operating cams 68, 68 respectively near the opposite ends of cylinder 4, and a pair of exhaust valve controlling cam mechanisms 69, 69 respectively 60 relatively close to, but on opposite sides of the median transverse plane of the cylinder 4. All of the cams mentioned are movably mounted upon the cam shaft 62, the admission valve actuating cam devices 68, 68 being connected for movement together through mechanism housed 65 within the shaft, and the exhaust valve controlling cam mechanisms 69, 69 being operatively connected together through devices also arranged inside the shaft but surrounding a portion of the adjusting means for cams 68, 68. The admission 70 valve controlling cams are automatically con-

trolled in accordance both with the speed of operation of the driving engine of which they form a part, and with the delivery pressure of the compressor which said driving engine actuates. The exhaust valve control cam devices 69, 69 are controlled by mechanism which is automatically responsive to the exhaust conditions of the driving engine, occupying one position when the engine is operating condensing and another when the engine is operating non-condensing, and automatically shifting to the last mentioned position in the event of loss of vacuum.

To describe further the structure of the admission valve controlling cams and the automatic control devices for said cams, before taking up the 15 structure of the exhaust valve control cam devices and the control mechanism of the latter, it may be noted that each of the admission valve control cams 68 is formed upon a sleeve 71 slidably mounted upon the exterior of the cam shaft 62. 20 These sleeves support cam projections 72 which have valve-opening-effecting, leading surfaces 73, and surfaces 74 for holding the admission valve open, and surfaces 75 for permitting closure of the admission valve. The surfaces 73, 74 and 75 25 are provided so that opening of the admission valve commences at the same instant in the cycle of piston travel irrespective of the position of the cam device 68 longitudinally with respect to admission valve actuating rollers 57. However, the 30 height of the cam portion proper and its width are both different longitudinally of the sleeve 71, with the result that when the right hand end of the sleeve is opposite the cam-actuated roller 57 of an admission valve, the valve is opened both 35 less long and less widely, while when the left hand end of the cam is opposite the roller the valve is held open for a longer period and is opened wider.

It will be observed that each of the sleeves 71 has a pair of aligned holes 77 through which there 40 extend pin elements 78 which pass through slots 79 in the wall of the hollow shaft 62 and through openings 80 in connected block elements 81 slidably mounted within the bore of the shaft. The blocks 81 are connected together by rod portions 45 82, and the left hand block 81 is connected to a further block 83 which likewise carries a transverse pin 84 extending through slots 85 in the hollow shaft 62. Between a collar 86 fixed to the periphery of the shaft 62 and a sliding sleeve 87 50 slidably mounted upon the exterior of the shaft 62 and connected to the block 83 by the pin 84 is arranged a spring 88 of appropriate strength to provide necessary resistance to the action of the speed responsive device, and also to the action of the pressure device above referred to and hereafter more fully described. The pin 84 has a projecting portion 90 connected by a suitable link 91 to another link 92 adjustably fixed as at 93 to one of a pair of parallel arms 94 pivotally supported 60 by pins 95 carried by a sleeve 96 fixed to the shaft 62 and carrying weights 97 of appropriate mass. It will be noted that as the shaft 62 is rotated, the weights 97 and arms 94 will tend to move under the action of centrifugal force towards a position 65 in which the arms 94 will lie in planes perpendicular to the axis of rotation of the shaft 62. Such a movement of the weights and arms will cause the linkage 92-91 to move the pin 84 and the sleeve 87, against the resistance opposed by the spring 88, toward the left, and will thus tend to move the rod 82 toward the left, which will result in a movement of the cam member 68 in a direction to diminish the period of admission valve 70 opening. As a result it will be noted that over- 75

- speeding of the compressor will cut down on the degree to which the admission valves open and also cause earlier cut-off, while any tendency to slow down on the part of the compressor will 5 result in a reduction in the centrifugal force exerted against the spring 88, and accordingly the latter will move the rod 82 to increase the quantity of steam admitted to the compressor cylinder and make cut-off come later.
- 10 The block 81 at the right hand extremity of the rod 82 has a rod 100 connected to it and extending into a cylinder forming member 101 mounted upon the right hand end of the housing 60. Within this member is a cylinder bore 102 in which a plunger 103 is reciprocably mounted. A ball 104 permits rotation of the rod 100 relative to the piston 103 without material friction. A laterally extending arm 105 is carried by the piston 103 and extends through an opening 106 and has secured thereto a rod-like member 107 carrying stop nuts 108 and 109 respectively, and these are adapted to engage the opposite sides of a lug 110 through an opening 111 in which the rod-like member 107 extends.
- 15 The nut 108 limits the extent to which the plunger 103 can move the rod 100 and the connected system leftwards. Nut 109 limits the distance that rod 100 and the connected system can be moved to the right by spring 88. Pressure is supplied through a connection 112 to the cylinder bore 102, such pressure being delivered under the control of a pilot mechanism 113 from a pipe 114 connected to the compressor discharge line. The device 113, which is of a well known commercial form, performs a dual 20 function. It reduces the pressure transmitted through it to a relatively small fraction of compressor discharge pressure. It also amplifies the changes in compressor discharge pressure. For example when the compressor discharge pressure desired is 125 pounds, this device will cut down the pressure transmitted say to 25 pounds, at the same time upon an increase of compressor discharge pressure to 126 25 pounds it will result in the transmission of a pressure of 30 pounds to the piston 103; and upon a reduction of one pound in the compressor discharge pressure, to 124 pounds, the pressure transmitted to the plunger 103 will be reduced 30 several pounds. Accordingly the pressure control is one of great sensitivity. One structure of the character described is sold under the name of Fisher Pilot Valve.
- 35 Now turning to the exhaust valve actuating devices, it will be noted that a pressure responsive device 115 provides a cylinder 116 in which a plunger 117 is reciprocable. This plunger is normally pressed in one direction by a spring 118; and the end of the cylinder 116 towards which plunger 117 is moved by the spring 118 is vented to atmosphere as at 119. Connection 120 at the opposite end, is led to the condenser to which the exhaust steam passes from the engine. Now, as long as a substantially sub-atmospheric condition is maintained in the condenser, it will be obvious that plunger 117 will be moved to the right as in Fig. 4, but upon the occurrence of a failure in condenser vacuum, the spring 118 will move the plunger 117 to the 40 left in Fig. 4. Plunger 117 is connected to an operating rod 121 pivotally connected as at 122 to an arm 123 of a yoke 124 which is pivotally mounted on a transverse pin 125, carried on the housing 60. The yoke carries pins 127 which extend into an arcuate member 128 which is 45 received in the groove 129 of a sleeve 130 slidably splined as at 131 to the exterior of the shaft 62. The sleeve 130 has a pin 132 extending through a slot 133 in the shaft 62 and engaging one end of a sleeve 134 slidably mounted inside the shaft 62 and surrounding and slidably relative to the rod 82. Another sleeve 136 is slidably splined as at 137 to the shaft 62 and has a pin and slot connection 138 with the sleeve 134. A spring 139 normally maintains the sleeves 136 and 130 as far apart as possible.
- 50 Each of the sleeves 130 and 136 has connected to it three cams. These cams include an exhaust valve opening cam 140, a left hand cam 141 controlling closure of the exhaust valve during condensing operation, and a right hand cam 142 controlling exhaust valve closure during non-condensing operation. Studs 143 extending through the cams and into the sleeves 130 and 136 respectively, and cooperating nuts 144 permit relative adjustment of the cams 141 and 142, each of which is slotted as at 145, relative to the cams 140 which are keyed as at 146 to the shaft 62.
- 55 Cams 140 are set substantially opposite each other with respect to the shaft 62, and their leading edges control the time when the exhaust valves are opened. The cams 141 and 142 control the time when the exhaust valves are permitted to close. Obviously cam 142 will keep 30 the exhaust valves open longer than cam 141. The rollers 57 are wide enough to engage cam 140 and either cam 141 or cam 142 concurrently. Both cams 141 or both cams 142 are operative 35 at the same time.
- 60 The mode of operation of this mechanism will be clearly understood by referring to Figs. 4, 5, 6, 7 and 8. During normal engine operation the cams 140 will effect release at the desired points in the cycle. During condensing operation, the 40 exhaust valves may be allowed to close relatively promptly and start compression relatively early in the strokes. Accordingly cams 141 will be employed to bring this result about and they will be adjusted into operative position by sliding of the sleeves 130 and 136 opposite the rollers 57. If the back pressure rises, due to loss of vacuum in the condenser, spring 118 will move the lever 123 to shift cams 141 out of cooperative relation with the rollers 57 and will bring 50 the cams 142 into position to engage the rollers, and thereby there will be produced a longer period of exhaust. It will be appreciated that the cams 140—the cams which control release—are continuously in operative relation with the 55 rollers 57, and that the cams 141 and 142, which respectively effect different delays before re-closure of the exhaust valves, with compression therefore occurring at different points in the engine cycle, are alternatively effectively in engagement with the rollers 57. When the engine is exhausting to a relatively low vacuum, the cams 141 contact with the rollers 57, while the cams 142 are completely out of contact with the rollers. When the engine is operating non- 60 condensing, the two cams 142 are in cooperative relation with the rollers 57, while the cams 141 have been moved axially out of contact with the rollers 57.
- 65 From the foregoing description it will be evident that I have provided an apparatus peculiarly adapted to the operation of compressors or other pumps. It will be obvious that this apparatus will automatically maintain a desired operating speed except as an excess of air or 70
- 70
- 75

other pumped fluid (due to diminished demand) may necessitate slower operation of the pump or compressor. It will be noted that in the event of loss of vacuum the condenser device will automatically prevent injury by extending the periods of exhaust. It will be evident that the apparatus is compact, and simple, and effective.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In an engine, in combination, a cylinder having a bore, a piston reciprocable in said bore, means for controlling admission to and exhaust from said cylinder bore including cam-operated admission and exhaust valves, a cam-supporting shaft rotatable during operation of said engine, longitudinally reciprocable cams mounted on said shaft for rotation thereby and of the variable-throw type for controlling admission and cut-off, longitudinally reciprocable cam means mounted on said shaft for rotation thereby and of varied dwell for controlling release and compression, means responsive to the load on said engine for automatically controlling the position of said cams longitudinally of said shaft, and means responsive to the back pressure in the engine exhaust for automatically controlling the position of said cam means longitudinally of said shaft.

2. In an engine, in combination, a cylinder having a bore, a piston reciprocable in said bore, means for controlling admission to and exhaust from said cylinder bore including cam-operated admission and exhaust valves, a cam-supporting shaft rotatable during operation of said engine, longitudinally reciprocable cams mounted on said shaft for rotation thereby and of the variable-throw, variable-dwell type for controlling admission and cut-off, longitudinally reciprocable cam means mounted on said shaft for rotation thereby and of varied dwell for controlling release and compression, means responsive to the load on said engine for automatically controlling the position of said cams longitudinally of said shaft, and means responsive to the back pressure in the engine exhaust for automatically controlling the position of said cam means longitudinally of said shaft.

3. In an engine, in combination, a cylinder having a bore, a piston reciprocable in said bore, means for controlling admission to and exhaust from said cylinder bore including cam-operated admission and exhaust valves, a cam-supporting shaft rotatable during operation of said engine, longitudinally reciprocable cams mounted on said shaft for rotation thereby and of the variable-throw type for controlling admission and cut-off, longitudinally reciprocable cam means mounted on said shaft for rotation thereby and of varied dwell for controlling release and compression, means responsive to the speed of said engine for automatically controlling the position of said cams longitudinally of said shaft, and means responsive to the back pressure in the engine exhaust for automatically controlling the position of said cam means longitudinally of said shaft.

4. In an engine, in combination, a cylinder having a bore, a piston reciprocable in said bore, means for controlling admission to and exhaust

from said cylinder bore including cam-operated admission and exhaust valves, a cam-supporting shaft rotatable during operation of said engine, longitudinally reciprocable cams mounted on said shaft for rotation thereby and of the variable-throw, variable-dwell type for controlling admission and cut-off, longitudinally reciprocable cam means mounted on said shaft for rotation thereby and of varied dwell for controlling release and compression, means responsive to the speed of said engine for automatically controlling the position of said cams longitudinally of said shaft, and means responsive to the back pressure in the engine exhaust for automatically controlling the position of said cam means longitudinally of said shaft.

5. In an engine, in combination, a cylinder having a bore, a piston reciprocable in said bore, means for controlling admission to and exhaust from said cylinder bore including cam-operated admission and exhaust valves, a cam-supporting shaft rotatable during operation of said engine, longitudinally reciprocable cams mounted on said shaft for rotation thereby and of the variable-throw type for controlling admission and cut-off, longitudinally reciprocable cam means mounted on said shaft for rotation thereby and of varied dwell for controlling release and compression, means responsive both to the speed of and load on said engine for automatically controlling the position of said cams longitudinally of said shaft, and means responsive to the back pressure in the engine exhaust for automatically controlling the position of said cam means longitudinally of said shaft.

6. In an engine, in combination, a cylinder having a bore, a piston reciprocable in said bore, means for controlling admission to and exhaust from said cylinder bore including cam-operated admission and exhaust valves, a cam-supporting shaft rotatable during operation of said engine, longitudinally reciprocable cams mounted on said shaft for rotation thereby and of the variable-throw, variable-dwell type for controlling admission and cut-off, longitudinally reciprocable cam means mounted on said shaft for rotation thereby and of varied dwell for controlling release and compression, means responsive both to the speed of and load on said engine for automatically controlling the position of said cams longitudinally of said shaft, and means responsive to the back pressure in the engine exhaust for automatically controlling the position of said cam means longitudinally of said shaft.

7. In an engine, a valve, an actuating plunger therefor, and cam actuating means for said plunger including cam means for providing for uniform valve opening movements thereof and separate cam means arranged at opposite sides of said first mentioned cam means respectively for providing for different valve closing movements thereof.

8. In an engine, a valve, an actuating plunger therefor, and cam actuating means for said plunger including cam means for providing for uniform valve opening movements thereof and separate cam means arranged at opposite sides of said first mentioned cam means respectively for providing for different valve closing movements thereof, said cam means having fluid operated controlling means governed by a pressure associated with the operation of the engine.

9. In an engine, a valve, an actuating plunger therefor, and cam actuating means for said plunger including cam means for providing for

uniform valve opening movements thereof and separate cam means arranged at opposite sides of said first mentioned cam means respectively for providing for different valve closing movements thereof, said cam means having fluid operated controlling means governed by the exhaust pressure of the engine.

10. In an engine driven pump system, an engine having a cylinder, a piston reciprocable in said cylinder, means for controlling admission to said cylinder including admission valves and valve controlling means variably controlled in accordance with the pump discharge pressure, and means for controlling exhaust from said cylinder including exhaust valves, valve controlling means variably controlled by engine back pressure to effect closure of said exhaust valves at different points in the travel of the engine piston in accordance with engine back pressure changes 15 and valve controlling means for opening said exhaust valves at substantially the same points in the travel of the engine piston irrespective of engine back pressure variations.

11. In an engine driven pump system, an engine having a cylinder, a piston reciprocable in said cylinder, means for controlling admission to said cylinder including admission valves and valve controlling means variably controlled in accordance with the pump discharge pressure 20 and the speed of operation of the pump, and means for controlling exhaust from said cylinder including exhaust valves, valve controlling means variably controlled by engine back pressure to effect closure of said exhaust valves at different points in the travel of the engine piston in accordance with engine back pressure changes and valve controlling means for opening said exhaust valves at substantially the same points in the travel of the engine piston irrespective of the engine back pressure variations.

12. In an engine, a valve, an actuating plunger therefor, and rotating cam means for actuating and controlling said plunger including cam means for effecting valve opening at a predetermined point in the cycle of said engine, and separate cam means arranged at opposite sides of said first mentioned cam means respectively and respectively effective to provide for valve closure at different points in the engine cycle.

13. In an engine, a valve, an actuating plunger therefor, and rotating cam means for actuating and controlling said plunger including cam means for effecting valve opening at a predetermined point in the cycle of said engine, and separate cam means arranged at opposite sides of said first mentioned cam means respectively and respectively effective to provide for valve closure at different points in the engine cycle, said cam means having fluid operated controlling means governed by a pressure associated with the operation of the engine for regulating their axial position.

14. In an engine, a valve, an actuating plunger therefor, and rotating cam means for actuating and controlling said plunger including cam means for effecting valve opening at a predetermined point in the cycle of said engine, and separate cam means arranged at opposite sides of said first mentioned cam means respectively and respectively effective to provide for valve closure at different points in the engine cycle, said cam means having fluid operated controlling means governed by the exhaust pressure of the engine for regulating their axial position.

15. In an engine, a valve, an actuating plunger therefor, and cam actuating means for said plunger including cam means for providing for uniform valve opening movements thereof, and separate cam means for providing for different valve closing movements thereof, said cam means having fluid operated controlling means governed by pressure associated with the operation of said engine.

16. In an engine, a valve, an actuating plunger therefor, and cam actuating means for said plunger including cam means for providing for uniform valve opening movements thereof and separate cam means for providing for different valve closing movements thereof, said cam means having fluid operated controlling means governed by the exhaust pressure of the engine.

17. In an engine, a valve, an actuating plunger therefor, and cam actuating means for said plunger including cam means for providing for uniform valve opening movements thereof, and separate cam means for providing for different valve closing movements thereof, said cam means rotatable to effect their controlling function and having fluid operated controlling means governed by a pressure associated with the operation of the engine.

18. In an engine, a valve, an actuating plunger therefor, and cam actuating means for said plunger including cam means for providing for uniform valve opening movements thereof, and separate cam means for providing for different valve closing movements thereof, said cam means rotatable to effect their controlling function and having fluid operated controlling means governed by the exhaust pressure of the engine.

19. In a valve operating mechanism, means for the operation of a single valve comprising a valve stem, a cam cooperating with said stem to effect opening of said valve at a predetermined point in the engine cycle, and separate cam means arranged at opposite sides of said first mentioned cam means and each controlling valve closure but respectively arranged to effect valve closure at different points in the engine cycle.

20. In an engine, a valve, a stem for said valve, and cam actuating and controlling means for said stem including rotating cam means providing for stem movement in one direction at a predetermined point in the engine cycle, and separate rotating cam means arranged at opposite sides of said first mentioned cam means respectively determining the opposite movements of said stem at different points in the engine cycle.

21. In an engine, a valve, an actuating plunger therefor, cam actuating means for said plunger including cam means for providing for uniform valve-opening movements thereof, separate cam means rotatable on a common axis with said first mentioned cam means for providing for different valve-closing movements of said plunger, and means automatically governed by predetermined changes in engine exhaust pressure for controlling said last-mentioned cam means.

22. In an engine, a valve, an actuating plunger therefor, cam actuating means for said plunger including cam means for providing for uniform valve-opening movements thereof, separate cam means for providing for different valve-closing movements of said plunger, said several cam means rotatable on a common axis and movable longitudinally of said axis, and means responsive to changes in back pressure on the engine for mov-

ing said cam means longitudinally of said axis to provide for different valve closing movements of said plunger.

23. In an engine, a valve, an actuating plunger therefor, and cam actuating means for said plunger including cam means for providing for uniform valve-opening movements thereof, a plurality of separate mutually coaxial cam means each providing for different valve closing move-

ments of said plunger, said plunger at all times subjected to control by said first-mentioned cam means and to one of said last-mentioned cam means, and means governed by engine exhaust pressure for automatically determining which of said last mentioned cam means governs valve closure. 5

ALEXANDER D. FERGUSON.
